UNITED STATES PATENT OFFICE

JAMES E. BURNS, OF BRIDGEPORT, CONNECTICUT, ASSIGNOR TO REMINGTON ARMS COMPANY, INC., A CORPORATION OF DELAWARE

AMMUNITION

No Drawing.

Application filed August 27, 1930. Serial No. 478,295.

This invention relates to priming mixtures for ammunition, and particularly to priming mixtures of the non-corrosive type, such mixtures being characterized by the absence of any ingredients which leave hygroscopic residues in the gun bore, thereby promoting corrosion and rusting of the bore. A few such mixtures are known at this time and owing to their highly desirable non-corrosive properties they have largely displaced the older corrosive mixtures.

The function of a priming mixture being to supply a flame of sufficient intensity and heat to ignite propellant powder, the priming compositions include two essential ingredients; first, a fuel or substance to be burned, and second, an oxidizer to furnish oxygen for the combustion of the fuel. A third ingredient, however, is quite universally used, the function of which, stated in very general terms is to initiate the reaction between the oxidizer and the fuel; thus, its essential characteristic is that it react under the stimulus of a blow to produce sufficient flame and/or heat to start the combustion of the fuel by the oxidizer.

As such a combustion initiator mercury fulminate has been very extensively used for a long period of time. Mercury fulminate, however, is undesirable for several reasons. It is expensive and dangerous to manufacture, and great difficulty is encountered in securing a product of uniform quality. Further, mercury fulminate is of a poisonous character and injurious to the health of the workmen who handle it or priming mixtures containing it. It also presents the disadvantage of amalgamating with the metal of cartridge cases and primer cups, rendering it incapable of use in primer cups and (rim fire) shells of such alloys as brass, which are otherwise highly desirable for this purpose.

The present invention contemplates a priming mixture which is not only non-corrosive but in which undesirable mercury fulminate has been replaced by materials which, while fully efficient as combustion initiators, can be safely made of uniform quality, are non-poisonous and easily handled, and permit the use for primer cups and rim fire shells of

metals and alloys, such as brass, which are attacked by mercury fulminate.

It has been found that admixtures of certain organic nitro compounds form satisfactory priming mixture sensitizers. For example, good results have been secured by the use of an admixture of a tetracene, such as guanylnitrosaminoguanylterracene, and a nitrated quinone-di-azide, such as the 4-6-dinitro-quinone-2-diazide, probably better known as "diazodinitrophenol".

Such an admixture may be used as the sole combustion initiating ingredient, or it may be used to sensitize another combustion initiator, such as lead trinitroresorcinate.

The "tetracenes" are a group of compounds which have as their distinguishing characteristic an open chain of four nitrogen atoms. The empirical formula for guanylnitrosaminoguanylterracene is $C_2H_8ON_{10}$, which may be structurally written as follows:

75

Diazodinitrophenol has the composition $C_6H_2N_4O_5$, and probably the structure

80

85

A combustion initiator of guanylnitrosaminoguanylterracene and diazodinitrophenol can be used in conjunction with the usual fuels, such as lead sulphocyanate and/or antimony sulphide and/or calcium silicide, and such non-corrosive oxidizers as barium nitrate, lead nitrate, lead peroxide, etc. Thus typical mixtures are as follows:

Diazodinitrophenol	35%	37%	95
Guanylnitrosaminoguanylterracene	2	3	
Lead nitrate	37	34	
Lead sulphocyanate	8	7	
Glass	18	19	100

A typical mixture in which guanylnitrosaminoguanyltetraacene and diazodinitrophenol are used with lead trinitroresorcinate is:

5	Diazodinitrophenol	4%
	Guanylnitrosaminoguanyltetraacene	1%
	Lead trinitroresorcinate	40%
	Lead nitrate	29%
	Lead sulphocyanate	7%

10 Glass 19%

It is to be understood, however, that these formulas may be greatly varied, both as to proportions and as to the particular oxidizing and fuel ingredients, the invention being limited only by a broad construction of the appended claims.

What is claimed is:

1. A priming mixture comprising an admixture of guanylnitrosaminoguanyltetraacene and diazodinitrophenol.
2. A priming mixture comprising an admixture of guanylnitrosaminoguanyltetraacene, diazodinitrophenol, an oxidizing ingredient, and a fuel ingredient.
- 25 3. A priming mixture comprising an admixture of guanylnitrosaminoguanyltetraacene, diazodinitrophenol, and lead nitrate.
4. A priming mixture comprising an admixture of guanylnitrosaminoguanyltetraacene, diazodinitrophenol lead nitrate, and lead sulphocyanate.
- 30 5. A priming mixture comprising substantially:

35 Diazodinitrophenol approximately 37%
 Guanylnitrosaminoguanyltetra-
 cene approximately 3
 Lead nitrate approximately 34
 Lead sulphocyanate approximately 7
 40 Glass approximately 19

6. A priming mixture comprising substantially:
 Diazodinitrophenol approximately 4%
 45 Guanylnitrosaminoguanyltetra-
 cene approximately 1
 Lead trinitroresorcinate approximately 40
 Lead nitrate approximately 29
 Lead sulphocyanate approximately 7
 50 Glass approximately 19

JAMES E. BURNS.

DISCLAIMER

1,862,295.—James E. Burns, Bridgeport, Conn. AMMUNITION. Patent dated June 7, 1932. Disclaimer filed March 20, 1935, by the assignee, Remington Arms Company, Inc.

Hereby enters this disclaimer to claims 1 and 2 of said patent, which claims are in the following words:

- “1. A priming mixture comprising an admixture of guanylnitrosaminoguanyl-tetraacene and diazodinitrophenol.
- “2. A priming mixture comprising an admixture of guanylnitrosaminoguanyl-tetraacene, diazodinitrophenol, an oxidizing ingredient, and a fuel ingredient.”
